UNITED STATES PATENT OFFICE

JOHN W. SCOTT, OF OAKLAND, CALIFORNIA

PAPER VENDING MACHINE

Application filed August 26, 1929. Serial No. 388,477.

This invention relates particularly to a means for dispensing predetermined lengths of paper from a roll in a closed container.

The object of the invention is to provide a simple coin controlled paper vending machine that will be economical to manufacture, of few parts, easily operated, strong, durable and highly efficient in its practical application.

10 In the drawings:

Figure 1 is a front elevation of the device with the closure raised.

Figure 2 is an end elevation of the same with the closure closed.

15 Figure 3 is a section on line 3—3 of Figure 1.

Figure 4 is an enlarged detail of the coin controlled actuating mechanism, parts broken away and partly in section.

20 The case 1 is provided with a hinged closure 2 provided with locking means as at 3. In the case are mounted vertical standards 4 having a roller mounted at 5 for carrying a roll of paper, and a pair of feeder rolls as at 6 and 7. A slot 8 is formed in the case below the feeder rolls.

25 In one end of the case is mounted a plate 9 having a hub 10 extending through the case and having a cam surface 11 formed on its outer end ending in an abrupt shoulder 12.

30 At 13 is a hand wheel mounted on a spindle 14 which has a reduced portion 15 revolvably mounted in the hub 10 and carrying a plate 16 to rotate upon the inner surface of plate 9. A cam surface 17 is formed in the shoulder 18 and ending in an abrupt shoulder 19 in opposed relation to the cam surface and shoulder 11 and 12 of hub 10 as shown.

35 In the spindle 14 is formed a bearing 20 to receive a shaft 21, a spring 22 being inserted between the end of the shaft and the end of the bearing to normally hold the opposing cam surfaces 11—17 in spaced relation to each other and to normally hold the plate 16 in contact with plate 9.

40 On the shaft 21 is mounted a gear 23 meshing with a small gear 24 on one feeder roll as 6, the ratio between the circumferences of the gears and rollers being such that one complete turn of the shaft 21 will rotate the

feeder rolls to deliver a predetermined length of paper. On shaft 21 is also mounted a bar 25 having a pin 26 set therein to engage holes 27 and 28 in plates 16 and 9, and on the opposite sides of the shaft to pin 26 is formed a slot 29 open on its outer end and on the edge toward plate 16. A spring 30 is inserted between the bar 25 and gear 23, and a coin chute 31 is mounted in the case with an entrance at 32 and positioned to discharge into slot 29 at end 33.

45 With a roll of paper mounted as at 34 and having an end extending downwardly between the feeder rollers and through slot 8, the device cannot normally be operated to feed additional paper because of the engagement between the plates 16 and 9 through the medium of pin 26. When, however, a coin is dropped into slot 29 the pin 26 may be withdrawn from the fixed plate 9 by 50 shoving the hand wheel inwardly; this movement causing the plate 16 to move inwardly and, through the medium of the coin, 35, to move the bar 25 inwardly together with the pin 26 mounted therein. The wheel 13 now 55 being rotated the coin drops out into the case on the half turn but the pin rides upon the surface of plate 9 until a complete revolution of the wheel has been made when it automatically drops back into the hole 28 and 60 the device is rendered inoperative until another coin is dropped into place. The engagement at 36 renders member 14 rotationally fixed but longitudinally movable on member 21.

65 The engaging cam surfaces 11—17 automatically withdraws the plate 16 from contact with the coin as the wheel is turned, thereby permitting the coin to fall out of the slot at the proper time and effectually 70 preventing the operator from carrying the coin around a second time.

75 It is to be understood, of course, that while I have herein shown and described but one specific embodiment of the invention, changes in form, construction, and method of assembly and operation may be made within the scope of the appended claims.

I claim:

1. A coin controlled paper vending ma- 100

chine comprising, a case having a slot formed therein, a pair of feed rolls mounted therein in operative relation to the slot, an operating shaft mounted therein and driving connections between the shaft and rollers, actuating means for the shaft resiliently mounted thereon for axial movement relative thereto but rotationally fixed relative thereto and operable from the exterior of the case, a plate 15 mounted on the inner end of the actuating means, a bar revolvably mounted on the shaft, resilient means for urging the bar toward the plate, a pin mounted in the bar and directed toward the plate, the plate and case 20 having alignable orifices formed therein to receive the pin, and the bar having a slot formed in the end thereof remote from the pin adapted to receive a coin and support the same in contact with the said plate, means 25 for introducing a coin into the slot from the exterior of the case, and means for releasing the inserted coin during rotation of the shaft.

2. A vending machine comprising, a case having a slot formed therein, feed rollers 25 mounted therein in operative relation to the slot, a drive shaft operatively connected to the rolls, actuating means for the shaft resiliently mounted thereon for axial movement relative thereto but rotationally fixed 30 relative thereto and operable from the exterior of the case, normally engaging plates mounted on the actuating means and case and having alignable orifices formed therein, a bar revolvably and resiliently mounted on 35 the shaft and having a slot formed therein to receive a coin and engage the same with the plate on the actuating means, means for introducing a coin to the slot from the exterior of the case, means for releasing the 40 inserted coin during rotation of the shaft, a pin mounted in the bar to engage the orifices in the said plates.

3. A vending machine comprising, a case having a slot formed therein, feed rollers 45 mounted therein in operative relation thereto, a drive shaft operatively connected to the rollers, actuating means for the shaft resiliently mounted thereon for axial movement relative thereto but rotationally fixed relative thereto and operable from the exterior 50 of the case, normally engaging plates mounted on the actuating means and case and having alignable orifices formed therein, a bar resiliently mounted for axial movement on 55 the shaft and having a slot formed therein to receive a coin and engage the same with the plate on the actuating means, means for introducing a coin to the slot from the exterior of the case, a pin mounted in the bar 60 to engage the orifices in said plates, and means operating to force the plate on the actuating means away from the bar when the actuating means is turned whereby to release the coin.

4. A vending machine comprising, a case

having a slot formed therein, feed rollers mounted therein in operative relation to the slot, a drive shaft operatively connected to the rollers, revoluble actuating means resiliently mounted on the shaft for axial movement relative thereto and projecting exteriorly of the case, a member slidably mounted on the shaft within the case, resilient means for urging said member toward the actuating means, normally engaging interlocking means inserted between the member and the actuating means and case whereby to prevent relative rotation between the same, means for introducing a coin edgewise between the member and actuating means 80 whereby a sliding movement of the actuating means inwardly of the case will impart a sliding movement to the member through the medium of the coin and disengage the interlocking means to permit rotation of the actuating means and member, means rendered operative by rotation of the actuating means to rotate the shaft, and means for releasing an inserted coin during rotation of the actuating means and member.
